UNITED STATES PATENT OFFICE

165,138

PILLAR MOUNTING BRACKET FOR AUTOMOBILE VISOR

Richard E. Dieterich, Long Beach, Ind.

Application June 23, 1950, Serial No. 10,720

Term of patent 14 years

(Cl. D14—6)

To all whom it may concern:

Be it known that I, Richard E. Dieterich, a citizen of the United States and resident of Long Beach, in the county of La Porte, and State of Indiana, have invented a new, original, and ornamental Design for a Pillar Mounting Bracket for Automobile Visor, of which the following is a specification, reference being had to the accompanying drawing, forming a part thereof:

Fig. 1 is a front elevational view of the pillar mounting bracket for automobile visor showing my new design.

Fig. 2 is an end-on view of the same taken from the top of the bracket as viewed in Fig. 1.

Fig. 3 is an end-on view of the same taken from the bottom of the bracket as viewed in Fig. 1.

Fig. 4 is a sectional view of the same taken through the bracket along the line 4—4 of Fig. 1 and in the indicated direction.

Fig. 5 is a vertical mid-sectional view taken through the bracket along the line 5—5 of Fig. 1 and looking in the indicated direction.

The rear of the bracket is devoid of ornamentation.

I claim:

The ornamental design for a pillar mounting bracket for automobile visor, substantially as shown and described.

RICHARD E. DIETERICH.
